UNITED STATES PATENT OFFICE.

FRED H. CONANT, OF GARDNER, MASSACHUSETTS, ASSIGNOR TO HEYWOOD BROTHERS & CO., OF SAME PLACE.

RATTAN ARTICLE.

SPECIFICATION forming part of Letters Patent No. 373,583, dated November 22, 1887.

Application filed July 11, 1887. Serial No. 213,941. (No model.)

To all whom it may concern:

Be it known that I, FRED H. CONANT, of Gardner, in the county of Worcester and State of Massachusetts, have invented a new and useful Improvement in the Art of Making Rattan Articles and the Like, of which the following is a specification, reference being had to the accompanying drawings, in which—

Figure 1 is a portion of the back of a chair embodying my invention, and Fig. 2 is a detail. Fig. 3 shows a portion of a chair-back embodying my invention wound in a different way from the back shown in Fig. 1.

Hitherto in rattan manufactures—chairs, cribs, lounges, baby-carriages, and the like—parallel strands have been stayed by scroll or Fitch work, and the consequence has been that the article in which the parallel strands have been thus stayed has lacked the rigidity and strength required to make the article durable and to keep it in shape; and my invention consists in staying the parallel strands by means of blocks fitted snugly between and secured to the strands, the blocks being wound with strands.

In the drawings, which show my invention embodied in a chair-back, A is the frame, and

a a cross-piece, to which the parallel strands b are attached in a well-known way.

In order to stay the parallel strands and to unite them with the desired rigidity and strength, I place blocks b' between the strands and secure the blocks in place and to the strands by brads or the like. (See Fig. 2.) When the blocks and strands are thus united, 35 the blocks are hidden from sight by other strands wound about them, as will be readily understood by all skilled in the art.

It is obvious that the blocks b' may be of any shape, so long as they have two sides parallel, and that they may be arranged in any desired relation to each other which will stay the strands.

What I claim is—

The herein-described improvement in rattan furniture, consisting in the combination of the parallel strands b and blocks b', securely fitted between the strands b and wound with other strands, substantially as and for the purpose set forth.

FRED H. CONANT.
